UNITED STATES PATENT OFFICE.

JOHN PURSELL, SR., OF NEW HAVEN, CONNECTICUT.

RECLINING-CHAIR.

SPECIFICATION forming part of Letters Patent No. 271,512, dated January 30, 1883.

Application filed October 9, 1882. (No model.)

To all whom it may concern:

Be it known that I, JOHN PURSELL, Sr., a citizen of the United States, residing at New Haven, in the county of New Haven and State 5 of Connecticut, have invented new and useful Improvements in Reclining-Chairs, of which the following is a specification.

My invention relates to improvements in chairs in which the back may be readily transformed from an upright into a reclining position, and the leg rest set at an angle by the occupant.

The particular matter which constitutes my improvement will be made the subject of specific claim, embracing in combination elements by which the back and the leg-rest can be adjusted by the occupant and supported in the desired positions.

Referring to the accompanying drawings, 20 Figure 1 represents a view in perspective of my improved reclining-chair; Fig. 2, a vertical section, showing the back and the leg-rest set for a reclining position; and Fig. 3, a similar view, showing the chair adjusted in position to form a couch.

The seat-frame *a* is secured to side frames, which constitute the legs and the arm-rest. The front and the rear legs, *b* and *c*, extend above the seat-frame in triangular form, the 30 rear legs being secured to the upper ends of the front legs, and the arm-rest *d* secured thereon and upon the upper end of a pillar, *d'*, secured to the seat-frame and to the rear legs, making a strong, firm, and durable frame. The 35 back is connected to the seat-frame by couplings *e*, in form like a bell-crank lever, being pivoted to the rear ends of the seat-frame *a* and to the side bars, *f*, of the back, so as to allow the back to have a swinging and vertical 40 movement upon the couplings. This double-pivoted connection given by the bell-crank levers allows the back to be turned as upon a pivot, and to have a limited rising and falling movement, by which it is rendered capable of 45 connection and adjustment at its lower end beneath the seat, with fixed curved slotted racks *g* secured to the seat and the rear legs. The side bars, *f*, of the back extend below the seat-frame, are curved forward, and provided with 50 inwardly-projecting headed pins *h*, adapted to be adjusted within the slots of the curved

racks. These racks are secured at their lower ends to the rear legs and at their upper ends to the inner sides of the side bars of the seat-frame, and are arcs of circles struck from a 55 point centrally between the pivots of the lever-couplings of the back, so as to give a movement to the back sufficient to allow it to assume a vertical or horizontal position. As the rack-plates are fixed and the headed pins move 60 within and engage with the teeth of their slots, the back must therefore have sufficient vertical play upon their coupling-levers to allow the pins to be freed from the teeth within the slot and to be moved over the teeth in the 65 curved slots in setting the back in the desired position. Without this vertical swinging capacity of the back it could not be combined with the fixed rack-plates having curved teeth forming one side of the curved slots. 70

For the purpose of maintaining the headed pins of the back in locked relation to the teeth of the slots, rubber or coil springs *i* are attached to the side bars of the back at a suitable point between their headed pins and their 75 pivoted couplings and to the forward ends of the seat-frame, so as to constantly exert a forward-pulling force upon the lower end of the back, and thereby maintain the headed pins in their set positions in the teeth of the racks, 80 holding the back secure when adjusted in the desired position. This construction of rack attachment and spring-connection of the back gives the important advantage of enabling the occupant to adjust the back as he may desire 85 for his ease. This he does by taking hold of the knobs *i'*, placed on the side bars of the back above the seat, and pulling the back upward and forward releases its headed pins from the rack-teeth, and, holding it in such position, its 90 lower end will be pulled forward and the back downward by the action of the springs until the desired inclination is given it.

To raise the back, the occupant pulls it to the front against the tension of the springs, and 95 when sufficiently raised he presses the back down, so as to bring its pins into the rack-teeth again. In this action the slots of the racks hold the back in proper connection therewith.

The leg-support *j* is pivoted to the front ends 100 of the seat-frame, and its side bars are provided each with a rack on their under side, while con-

neeted arms *k*, hinged to the front legs, are adapted to engage with the racks of the leg-support and sustain it in the desired position.

To allow the occupant to have control over the leg-rest to set it as he may wish, a lifting-cord, *l*, on one side of the cbair, is attached at or near the free ends of the leg-rest, and passes through an eye, *m*, in the arm-rest in position to be pulled by the occupant to raise the leg-rest; but as the connection of the hinged arms with the leg-rest racks is maintained by a spring, *n*, connecting said arms with the leg-rest, it is necessary to pull down the hinged arms to allow the leg-rest to be lowered. For this purpose a pulling-cord, *r*, on the other side of the chair, is attached to the hinged arms, and, passing under the ring *b'* of the front legs and over a pulley, *s*, in the seat-frame, is run through an eye, *t*, on the arm-rest, in position to be pulled by the occupant to depress the rack-arms to allow the leg-rest to be let down, as shown by dotted lines in Fig. 3. The spring-connection of the leg-rest and its supporting-arms allow the latter to follow up in contact with the leg-rest in raising it, and thus catch in the teeth and sustain leg-rest secure at the desired position. In this way the right and left hand cords serve to place the control of the leg-rest under the occupant, either to raise it or to lower it to suit his comfort, by having separate cord-connections for the pivoted leg-rest and its hinged ratchet-arms, and connecting these two parts by a spring.

The leg-rest may be provided with a hinged foot-support, which may be attached so that it can be adjusted as may be desired. The pulling-cords are provided with suitable hand-pulls. The back may be provided with an adjustable head-rest of any suitable construction.

40 I claim—

1. The combination, in a reclining-chair, of the fixed bars *g*, having each a slot forming

rack arranged upon each side of the chair-frame, one end of each connected to the seat-frame, and both, extending downward toward the back, 45 are connected to the rear legs, with the back having headed pins adapted for adjustment with the rack-teeth within said slotted bars, and the hanging couplings *e*, pivoted to the side bars, *f*, of the back and to the seat-frame, 50 whereby to allow the back to be adjusted within the said fixed slot forming racks, substantially as described.

2. In combination, in a convertible chair, the slotted bars *g*, secured to the seat-frame and 55 to the rear legs, having rack-teeth on one side of the slot, the back having headed pins working within said rack-slots, the hanging couplings *e*, pivoted to the seat-frame and to the back, and the springs *i*, arranged to exert a 60 forward-pulling force upon the back below the pivoted couplings, substantially as described, for the purpose specified.

3. In a convertible chair, the combination of the pivoted leg-rest *j*, having racks, and its 65 supporting hinged rack-arms *k*, with a spring, *n*, adapted to pull the rack-arms *k* into the leg-rest racks and to hold them in such connection, a cord, *l*, connected with the leg-rest, by which to elevate it, and a cord, *r*, connected 70 with the hinged rack-arms, adapted to exert a downward pull upon them against the upward pull of the cord *l*, whereby the leg-rest and its supporting rack-arms are separated against the force of the spring to adjust the leg-rest, 75 substantially as described, for the purpose specified.

In testimony whereof I have hereunto set my hand in the presence of two subscribing witnesses.

JOHN PURSELL, SR.
